UNITED STATES PATENT OFFICE.

BENJAMIN S. McCLELLAN, OF CHICAGO, ILLINOIS, BY ELNATHAN C. COOK, CONSERVATOR, OF CHICAGO, ILLINOIS; KATE B. McCLELLAN, NOW CONSERVATOR BY COURT ORDER IN LIEU OF SAID ELNATHAN C. COOK, RESIGNED.

TRACK LINER.

Application filed February 1, 1926. Serial No. 85,311.

This invention relates to track liners.

One object of the invention is to provide a track carrying lever adapted for insertion under the rail and movable transversely thereof for shifting the track for aligning purposes.

A further object of the invention is to effect the movement of said lever through the medium of a rock arm so as to limit the raising of the lever when aligning the track to prevent undue lifting of the ties from the roadbed to prevent ballast entering beneath the ties for disturbing the foundation therefor.

A further object of the invention is to provide means having a ratchet action to allow for a step by step application of power for shifting the rails and ties and retaining the track in its shifted positions between each application of power.

A further object of the invention is to obtain this ratchet action through the medium of an inclined rack on which the leverage applying bar has a step by step action in the shifting of the track.

A still further object of the invention is to have the track carrying lever connected with the leverage applying bar closely adjacent the fulcrum of the latter so as to increase the leverage applied by the bar in aligning the track.

The invention consists further in the matters hereinafter described and claimed.

In the accompanying drawings—

Fig. 1 is a side elevational view of a track liner constructed in accordance with the invention;

Fig. 2 is a longitudinal vertical sectional view through the same;

Fig. 3 is a top plan view of the same;

Figs. 4 and 5 are vertical sectional views taken on lines 4—4 and 5—5, of Figs. 2 and 1, respectively;

Fig. 6 is a side view showing an inclined block attached to the aligning lever for converting the device into a lifting jack;

Fig. 7 is a vertical sectional view on line 7—7 of Fig. 6; and

Fig. 8 is a view of a modified detail of construction to be hereinafter described.

As shown in the drawings, the track liner of the invention has a relatively flat base plate 1 provided on its under side with ribs

2, 3 for strengthening the plate and for engaging the underlying roadbed to hold the liner against slippage when in use. The ribs 2, 2 extend along the sides of the plate 1 and, as shown in Fig. 4, have inclined inner sides to hold and pack the roadbed between them and thus build up a foundation to resist the downward pressure on the plate. The ribs 3, 3 extend crosswise of the plate 1 and serve to prevent endwise shifting of the base plate in the use of the device. These ribs, as shown in Figs. 1 and 2, are substantially V-shaped so as to wedge into the roadbed.

Arranged above the base plate 1 and disposed to extend lengthwise thereof is an aligning lever 4 having its forward end free and supported by the base. This support includes a roller 5 journaled on the base in upright webs 6, 6 integral with said plate. The rear or opposite end of the lever 4 is pivoted to a rock arm 7 through an axis member 8. Said arm 7 is disposed beneath the lever 4, and the latter is hollowed out or made channel shaped so as to accomplish the arm, as shown in Figs. 2 and 4. Also by making the lever 4 in this shape, it is provided with vertically disposed side flanges 80 for giving added strength to the member. The lower end of the arm 7 pivots or rocks on an axis member 9 extending between and supported by the webs 6, 6, as shown. Said lever 4 has a cross-web 10 in its channel at its outer end to provide a continuous bearing for the roller 5 in the endwise movement of the lever 4.

To the rear of the arm 7 is an actuating lever 11 preferably made in socket form to receive an actuating bar 12, such as a standard track bar. The lever 11 is connected with the axis member 8 by a pair of links 13, 13, and the forward or fulcrum end of said lever 11 acts on an upwardly inclined rack means 14 for imparting a step by step action for lifting and shifting a track rail 15 through the aligning link 4, in the manner to be presently described.

This rack means 14, as shown in the drawings, is in the form of a pair of racks 16, 16 on the webs 6, 6 to the rear of the axis member 9. Each rack 16 is inclined upwardly and forwardly from the base plate 1, and is provided with a plurality of ratchet steps 17, 17 starting at the lower end of the rack.

The forward end of the actuating lever is bifurcated, as shown, so as to have a pair of end portions for engaging the pair of racks 16 and also to receive the pair of links 13, 5 the latter having pivotal connection with the lever 11 by a transverse pin 18. Pawls 19, 19 are carried by the axis member 8 to co-operate with the steps 17 in the actuation of the device. These pawls are connected together 10 by a transverse web 20 so that they operate in unison.

In use, the device is inserted under the rail 15 until the lever 4 contacts with the adjacent edge of the base flange of the rail, 15 as shown in Fig. 1. If the space between the base flange of the rail and the roadbed is at the minimum, say three inches, the lever 4 is in a position substantially horizontal and with the pawls 19 free of the steps 17 20 and resting against the base plate 1 at the lower ends of the racks 16, as shown in Fig. 1. This will enable the liner to be inserted under the rail so as to bring the adjacent edge of the rail preferably midway between 25 the axis of the roller 5 and the axis member 8. At this time the forward or fulcrum end of the actuating lever 11 is in position to engage the lowermost of the steps 17.

On raising of the bar 12, the lever 11 ful- 30 crums on the lowermost steps 17 and rocks the arm 7 forward to raise the rear of the lever 4 and thereby lift the rail 15 and its attached ties to break contact of the latter with the roadbed to lessen the resistance to 35 the shifting of the rail and its ties in the aligning of the track. The pawls 19 ratchet up the first steps 17 and hold the lever 4 in its raised position to retain the rail 15 and its ties raised. With the pawls 19 re- 40 taining the load, the lever 11 is free so that its outer end may be lowered to raise its fulcrum end to engage the next set of steps 17, the links 13 gravitating inward to automatically swing the fulcrum end of said lever in- 45 to said steps. This allows for another application of power or leverage to the lever 4 to advance it farther forward and carry the rail 15 and its attached ties therewith.

The lever 11 and the pawls 19 act in a 50 similar manner as the lever 11 is engaged with the next succeeding steps to further advance the aligning lever 4. Said pawls retain the load on each release of the lever 11 from the racks and prevent the track 55 from receding and losing the force or power applied to shift it. This is an important feature of the invention because it allows the power or leverage exerted on the track through the lever 11 to be multiplied with 60 each successive power operation of said lever 11, thereby allowing a single workman to exert considerably more leverage or power on the track to shift the same than with track lining devices as heretofore made. 65 By holding the track from receding between

each power operation of the lever 11, the track is retained in its various intermediate shifted positions, thus making the device more effective. Moreover, the track does not spring back to jar and loosen the dirt or ballast of the roadbed to enter beneath the slightly raised ties to disturb the foundation therefor.

As the advance of the lever 4 increases, 70 the lifting of the lever decreases as the arm 7 approaches a vertical position. This is another important feature of the invention because the ties are not lifted high enough to permit ballast to enter between them and the roadbed to disturb the foundation for the track. In the initial application of power to the device when the lever 11 engages the lowermost steps 17, the base plate 1 is forced into the ground so as to obtain a proper seat until sufficient resistance is obtained to lift or support the rail and attached ties in the advance of the lever 4. Consequently, by having the track engage the lever 4 in the midway position heretofore mentioned, the amount of lifting given in the track is necessarily limited, due to the loss caused by base plate 1 being pressed into the ground, and therefore undue lifting of the track to build up ballast beneath the ties is avoided. The track is therefore shifted substantially horizontally in the advance of the lever 4 so that no opportunity is offered for building up of ballast beneath the ties.

It will be noted that the forward or fulcrum end of the lever 11 on engaging the steps 17 exerts a downward pressure on the base plate 1 on one side of the rail in the upward movement of the lever, while the weight of the rail on the lever 4 is exerted 100 downward on the plate 1 on the opposite side of the rail through the roller 5, thereby practically equally distributing the load on the base plate. The pawls 19 engaging the racks 16 adjacent the fulcrum end of the lever 11, also effect an equal distribution of 105 load when said lever is free.

The axis member 9 has a fixed position on the base plate 1 and does not change in the actuation of the device. The roller or bearing 5 is also in a fixed position on the base plate and does not change as the lever 4 advances or recedes over the same. This provides a fixed distance between the bearing 5 and axis member 9 so that the distance between the outer end of the lever 4 and the axis member 9 varies in the rocking of the arm 7. As the arm 7 rocks or swings forward, that is, toward the rail 15, the latter is carried by the lever 4, and as the rail approaches closer to the fulcrum 5 of said lever 4 the leverage on the latter gradually increases to overcome the increasing resistance offered to the forward ends of the ties by the ballast building up in front of the same 130

as the track is shifted. The gradual increase in leverage is accomplished by the forward or free end of the lever 4 traveling beyond the bearing or fulcrum 5 and shortening the distance between the point of bearing of the rail on the lever 4 and its fulcrum 5 without changing the distance between said rail and the pivoted end of said lever 4.

The racks 16, 16 are located to the rear of the axis member 9 so that the lever 11 cannot move the arm 7 beyond a substantially upright or vertical position, as shown in Fig. 2. This prevents the lever 4 from carrying the rail 15 beyond the bearing 5 to overbalance the device and cause the leverage exerted through the same to become ineffective.

With a device of the general size shown in the drawings, a single workman may exert a leverage as follows. The distance between the axis member 18 and the fulcrum end of the lever 11 is approximately 1½ inches. A standard track bar, such as 12, is about 66 inches long, and with three inches between the pointed end of this bar and the fulcrum end of the lever makes an overall length of 69 inches. This provides a leverage exerted through the lever 11 and bar 12 (the latter being an extension of the former) of 46 to 1. When the lever 4 engages the rail 15 midway between the roller 5 and axis member 9, as heretofore stated, the lever 4 has a ratio of 2 to 1 so as to double the effective leverage of the lever 11. This initial ratio of lever 4 increases to 2½ to 1 as the rail approaches the fulcrum 5, thus compounding the leverage exerted by the device in the shifting of the rail. In this present device the maximum shift of the rail is approximately five inches. In practice, two of the devices will be employed at the same time, one for each rail, and arranged directly opposite so as to effect proper shifting of the track.

In the first application of power, a large portion of the leverage exerted through the levers 4 and 11 is generally employed to lift the dead load of the rail and its attached ties. As the rail approaches closer to the fulcrum 5 in the movement of the lever 4, this dead load is transferred closer to the fulcrum to lighten the load on the lever 11 so as to increase the power effect of the latter for shifting the track.

A loop handle 21 is provided at the pawls 19 so that the latter may be manually raised up the racks 16 to adjust the lever 4 upward under the rail for contact therewith to accommodate for varying distances between the road bed and the rail. This handle may be made integral with the pawls and includes the cross-web 20.

This handle also allows the device as a whole to be lifted and be carried from place to place. Additional handles 22, 22 extend laterally outward from the webs 6, 6

at the upper ends of the racks 16 to facilitate inserting the device under a rail and pulling the same therefrom.

The handle 21 also allows the pawls to be stepped down the rack 16 on the lowering 70 the lever 4 from contact with the rail. To accomplish this, the fulcrum end of the lever 11 is first engaged with the steps 17 on which the pawls rest, and then by raising upward 75 on the lever the load is transferred from the pawls to the lever 11, whereupon the pawls may be stepped down to the next steps 17 below by swinging them out by the handle 21. To step the lever 11 down the racks 17, 80 a grip handle 23 is provided at the outer end of said lever, said handle being grasped to swing the fulcrum end of said lever outward from the steps.

To use the device as a jack for lifting the rail vertically and not shifting the same laterally, an attachment is provided for the free end of the lever 4. This attachment is in the form of a block 24 having an inclined under surface 25 to ride on the roller 5, as shown in Fig. 6. The block has a 90 projection 26 on its top to enter an opening 27 at the forward end of the lever 4. This opening is provided by the web 10, as shown.

The roller 5 is grooved, as shown in Figs. 95 7 and 8, so as to provide a guide for the block to hold it from lateral displacement. The block when engaged with the lever 4 disposes the same substantially horizontal and maintains the lever in substantial parallelism 100 with the base plate 1 as the arm 7 is rocked to raise or lower the member 4 for jacking purposes. The pawls 19 act as before and hold the member 4 in its elevated positions.

The racks 16 may be provided with upright 105 guide flanges 28 along their outer side edges, as shown, to prevent the pawls shifting laterally off the racks.

The front of the plate 1 is notched, as at 110 29 to receive the forward or free end of the lever 4 when shifting a rail, as shown in Fig. 2. The web 10 may be set up into the lever 4 so that the side flanges of the bar embrace the roller 5^a, as shown in Fig. 8, to guide the bar. As shown in Figs. 2 and 6, the 115 roller 5 and the lower end of the arm 7 work in depressions or recesses 1^a, 1^b in the base 1, so as to reduce the overall height of the device especially when collapsed, as shown in Fig. 2, to be inserted under a rail. 120

The details of structure shown and described may be variously changed and modified without departing from the spirit and scope of the invention.

What is claimed as the invention is:

1. A track liner having a base, a rock arm having a fixed pivotal connection with the base, an aligning lever having one end pivoted to said arm and the other end free, a roller carried by the base and providing a 130

- support for the free end of said lever, said roller being at a fixed distance at all times from the pivotal connection of the arm with the base, and means for actuating said arm.
5. 2. A track liner having a base, a rock arm having a fixed pivotal connection with the base, an aligning lever having one end pivoted to said arm and the other end free, and a bearing on the base for the free end of the lever, said bearing being disposed to have the free end of the lever travel beyond the same in the forward actuation of said lever.
10. 3. A track liner having a base, a rock arm having a fixed pivotal connection with the base, an aligning lever having one end pivoted to said arm and the other end free, a bearing on the base for supporting the free end of the lever, said bearing being forward of the point of engagement of the lever with a rail so as to increase the leverage of the lever in the forward shifting thereof.
15. 4. A track liner having a base, a rock arm having a fixed pivotal connection with the base, an aligning lever having one end pivoted to said arm and the other end free, a bearing on the base for supporting the free end of said lever and allowing the lever to travel past the same, said bearing being disposed so as to be in a position forward of the point of engagement of the lever with a rail in any position of the lever so that the application of force on the lever in shifting the rail will be to the rear of said bearing.
20. 5. A track liner having a base, a rock arm having a fixed pivotal connection with the base, an aligning lever having one end pivoted to said arm and the other end free, a roller on the base and constituting a bearing for free end of the lever, said lever being hollowed and having a web at its forward end to ride on said roller, and means for actuating said arm.
25. 6. A track liner having a base, a rock arm pivoted thereon, an aligning lever having one end pivoted to said arm and the other end free, a bearing on the base for supporting the free end of said lever, said lever having an attachment for its free end for maintaining the lever in substantial parallelism to the base in the actuation of said arm.
30. 7. A track liner having a base, an arm pivoted thereon, an aligning lever having one end pivoted to said arm and the other end free, a bearing on the base to support the free end of said lever, said lever having an opening at its forward end and an attachment having a lug to extend into said opening, said attachment having an inclined under surface to ride on said bearing in the movement of the arm to maintain the lever substantially parallel to the base, and means for actuating said arm.
35. 8. A track liner having a base, an arm pivoted thereon, an aligning lever having one end pivoted to said arm and having its other end supported by said base, an actuating lever for operating said arm, and means enabling the fulcrum of the actuating lever to be advanced in the actuation of said arm.
40. 9. A track liner having a base, a rock arm having a fixed pivotal connection with the base, an aligning lever pivoted at one end to said arm and having the other end supported by said base, an upwardly inclined rack on the base, an actuating lever having its fulcrum end co-operating with said rack, a link connecting the actuating lever to the free end of said arm, and a pawl carried by the arm and ratcheting on said rack, the connection between the link and the actuating lever being relatively close to the fulcrum end of the latter so that the link in gravitating inward as the actuating lever is swung downward to advance its fulcrum up the rack will swing the fulcrum end into engagement with the teeth of the rack.
45. 10. A track liner having a base, a rock arm pivoted thereon, an aligning lever having one end pivoted to said arm and the other end supported by said base, an upwardly inclined rack on said base, an actuating lever linked to said arm and having its fulcrum advanced upward along the rack in the actuation of said lever, and a pawl ratcheting on said rack for retaining the aligning lever in its shifted position.
50. 11. A track liner having a base, a rock arm pivoted thereon, an aligning lever having one end connected with said arm and the other end supported by the base, a pair of upwardly inclined racks supported by said base on opposite sides of arm, an operating lever linked to said arm for actuating the same by having its fulcrum advanced up said racks, and a pair of pawls carried by said arm and ratcheting on said racks.
55. 12. A track liner having a base, a rock arm pivoted thereon, an aligning lever having one end supported by said base, an axis member connecting the other end of the lever with said arm, an operating lever, link means connecting the operating lever with said axis member relatively close to the fulcrum end of said lever, an upwardly inclined rack along which the fulcrum end of the operating lever is advanced in actuating said arm, and a pawl connected with said axis member and ratcheting on said rack.
60. 13. A track liner having a base, a rock arm pivoted thereon, an aligning lever having one end pivoted to said arm and the other end supported by said base, an upwardly inclined rack on said base, an actuating lever linked to said arm and having its fulcrum end advanced along said rack in the actuation of said lever, a pawl associated with the aligning lever and ratcheting on said rack, and a handle connected with said pawl.

for lifting the track liner and also releasing the pawl from the rack.

14. A track liner having a base plate, a rock arm pivoted thereon, an aligning lever having its forward end supported by said base plate, an axis member connecting the rear end of the lever with the upper end of said arm, upwardly inclined racks on said plate, an operating lever having its fulcrum advanced along said racks in the actuation of said lever, a link connecting the fulcrum end of the lever with said axis member, pawls carried by said axis member and ratcheting on said racks, a handle member connecting the pawls for uniform movement thereof, and hand grips on the base on opposite sides of said racks.
15. A track liner having a base plate, a

rock arm pivoted on said plate, an aligning lever having one end pivoted to said arm 20 and the other end supported by said plate, an upwardly inclined rack on the plate, an actuating lever linked to said arm and having its fulcrum advanced upward along the rack in the actuation of the lever, a pawl 25 associated with the lever and ratcheting on said rack, said actuating lever having a socket to receive a track aligning bar, and grip handles on the lever and pawl, respectively.

In testimony whereof I affix my signature this 29th day of January, 1926.
